UNITED STATES PATENT OFFICE.

ALBERT W. STOSSMEISTER, OF NEWPORT, KENTUCKY.

STOVE-PIPE SHELF.

SPECIFICATION forming part of Letters Patent No. 284,256, dated September 4, 1883.

Application filed May 5, 1883. (No model.)

To all whom it may concern:

Be it known that I, ALBERT W. STOSSMEISTER, a citizen of the United States, residing at Newport, Campbell county, Kentucky, have invented new and useful Improvements in Stove-Pipe Shelves, of which the following is a specification.

My invention relates to stove-pipe shelves, its object being the construction and arrangement of a shelf secured upon the stove-pipe and having a rotative action thereon, enabling it to be rotated out of the way when out of use. It also consists in the combination therewith of a casing extending downward to the top of the stove, and constituting therewith a temporary oven for warming purposes.

My invention is illustrated in the accompanying drawings, in which Figure 1 is a plan view of the shelf in position; Fig. 2, a partial sectional elevation of the same; Fig. 3, a plan and edge view of the holding-arms detached; Fig. 4, a front elevation of the shelf with oven attachment; and Fig. 5, a partial plan view, showing a modified form of attaching the shelf 25 to the pipe.

Parts referred to herein are indicated upon the drawings by letters of reference.

The shelf A is preferably of rectangular form, with a semicircular recess at one side to fit upon the pipe. The pipe B, which forms the pivot and sustaining-post of the shelf, is preferably a cast section of pipe adapted to fit the stove and extend upward a sufficient distance to maintain the shelf at a proper elevation above the surface of the stove. The section B of pipe is preferably formed, when cast, of two parts, fitted together and constituting a cylinder, and is provided at a suitable height with a circumferential flange, b, which forms 35 the rotating support for the shelf. The shelf is recessed around the margin of its semicircular edge to form a seat upon the flange b, and is secured to its position upon the pipe by two semicircular arms, c c, secured to the under side of the shelf at its recessed edge, and extending beneath the flange b, partly or wholly 40 around the pipe B, thus preventing the lateral

withdrawal of the shelf by forming a yoke around the pipe, and maintaining the shelf in a horizontal position by engaging the under side of the flange b at the opposite side of the pipe. The construction is clearly shown in Figs. 1, 2, 3. A modification of this construction is shown in Fig. 5, in which the arms c c are dispensed with and three holding-lugs, d, (indicated by dotted lines,) are secured to the under side of the shelf, extending radially beneath the flange b, and the shelf is prevented from lateral withdrawal by a wire or band, e, attached to the edges of the shelf and extending around the pipe. This construction permits the shelf to be rotated out of the way when out of use, and constitutes the primary feature of my invention.

A further improvement consists in providing a casing of sheet metal, C, secured to the outer margin of the shelf, and extending thence downward to the top of the stove, provided in front with a suitable opening, and a sliding door, C', by which the structure can be conveniently used as a warming-oven.

It is obvious that these features of my invention may be separately used with advantage, and need not therefore be used together unless desired, but that the rotating action of the shelf is equally advantageous with the oven attachment.

I claim as my invention and desire to secure by Letters Patent—

1. In combination with the shelf A, adapted to fit upon and around the flange b upon the stove-pipe, the arms c c, embracing the pipe and forming supporting-arms for the shelf, substantially as specified.

2. In combination with the rotating shelf A, the casing C, constituting, with the shelf, a movable oven, substantially as set forth.

In testimony whereof I have hereunto set my hand in the presence of two subscribing witnesses.

ALBERT W. STOSSMEISTER.

Witnesses:

L. M. HOSEA,
ALEX. HAMILTON.
